UNITED STATES PATENT OFFICE.

HUGO GERNBSACK, OF NEW YORK, N. Y.

ELECTROMAGNETIC SOUNDING DEVICE.

1,354,389.

Specification of Letters Patent. Patented Sept. 28, 1920.

Application filed December 11, 1917. Serial No. 206,636.

To all whom it may concern:

Be it known that I, HUGO GERNBSACK, a citizen of the United States, residing at New York, in the county of New York, State of New York, have invented certain new and useful Improvements in Electromagnetic Sounding Devices; and I do hereby declare the following to be a full, clear, and exact description of the invention, such as will enable others skilled in the art to which it appertains to make and use the same.

This invention relates to mechanisms for practising telegraphy and more particularly for use in practising wireless telegraphy wherein the signals have a degree of continuity as distinguished from the sharp clicks from the ordinary telegraph sounders. In the present apparatus, each depression of the key results in the vibration of a diaphragm in synchrony with a succession of electrical impulses of a duration corresponding to the length of time the key is held depressed. The result is a sound similar in quality to that given out by the wireless telegraph receiver, but many times amplified. The result is accomplished by placing a diaphragm in the field of force of an electro-magnet, in the circuit of which and of a sending key, is a make-and-break mechanism entirely independent of the diaphragm but actuated by the same electro-magnet.

In the drawings:—

Figure 1 is a view partially in section and partially in side elevation showing the complete apparatus.

Fig. 2 is a plan view with the diaphragm and casing cap removed.

Referring to the drawings, there is illustrated a base 5 of any suitable material at one end of which there rises an annular flange 6 that constitutes a cylindrical casing, the upper end of which is exteriorly threaded as shown at 7 to receive a cap 8 having a central opening in which is secured an amplifying horn 9. The extreme upper edge portion of the flange 6 is reduced in thickness as shown at 10 and from the lower face of the cap 8 there depends an annular flange 11 of the same diameter as the portion 10 and between which and the portion 10 is clamped a paramagnetic diaphragm 12 which is thus free to vibrate.

A bridge piece 13 of insulating material is supported at one end upon a block 14 and is held in such position by means of a bolt 15 passed through the bridge plate, block, and

base 5, as illustrated. The other end of the bridge plate, which extends diametrically of the casing formed by the flange 6, is supported upon a series of superimposed washers 16, 17 and 18, through which, the bridge piece and the base 5 is engaged a clamping bolt 19.

Through the bridge piece 13 and in axial alinement with the diaphragm 12 and amplifier 9, is disposed the core 20 of an electro-magnet that includes also the winding 21, the core extending into close relation to the diaphragm so as to effect its vibration without making physical contact.

Beneath the bridge piece 13 is disposed a make-and-break mechanism including a stationary metallic plate 22 one end of which is clamped between the fiber washers 17 and 18, the latter having a central hub that enters a corresponding opening in the plate 22 and abuts the washer 17, thus insulating the plate 22 from the bolt 19. Between the fiber washer 17 and the metal washer 16 is disposed a paramagnetic armature 23, the plate and arm having the usual platinum contact points as illustrated, and which lie normally in mutual contact. The parts are clamped in this correlation by means of the bolt 19.

The arm or vibrator 23 is within the field of the electro-magnet and it will be understood that when the magnet is energized, the vibrator will be attracted to separate the contact points.

Upon the base 5 exterior to the flange 6, there is disposed a post 24 that supports one end of a spring lever key 25 held thereon by means of a bolt 26 passed through the key, the post and the base, as illustrated. The key is provided with a platinum contact 26' which is normally out of engagement with a contact 27 in the form of a bolt that passes through the base 5.

Upon the base 5 are mounted binding posts 27' and 28 of which the post 27' is connected by a wire 29 with the bolt 26 through the medium of its nut as illustrated and thence with the key 25. The contact 27 is connected by wire 30 with one terminal 21' of the electro-magnet, the other terminal of which is connected by wire 31 with the arm 22. A wire 32 is clamped beneath the nut 19' of the bolt 19 and leads to the binding post 28.

With the construction above illustrated and described, it will be understood that the

posts 27 and 28 being in circuit with a source of electricity and the key 25 being depressed, the electro-magnet will be instantly energized which will effect a synchronous movement of the diaphragm 12. At the same time, the vibrator 23 will be moved to disengage its contact from that of the arm 22, thus breaking the circuit. The key being still depressed, the vibrator will instantly return to reengage the contacts, at which time the diaphragm will be released. At the instant of reengagement of the contacts, the electro-magnet will be reenergized and a second movement of the diaphragm and of the vibrator will result. This operation will continue so long as the key is held depressed and in practice, the vibrator is so proportioned as that its period of vibration will result in such vibration of the diaphragm as will give forth a tone such as is given by the receiver in the practice of wireless telegraphy.

In the instruments that are at the present time being placed upon the market, the parts are proportioned to give a tone corresponding to that produced in a wireless receiver operating on five hundred cycles.

The advantage in the use of this instrument is that the sounds emanating from the horn, while being very much louder than from a wireless receiver in use, are in tone quality and physical character in all respects similar to those received in wireless telegraphy.

In order to reduce the field resistance of the electro-magnet, a U-shaped paramag-

netic plate 33 is sprung over the electro-magnet and the bridge piece, one arm of the U-shaped plate being secured against the lower end of the core of the electro-magnet 40 through the medium of a paramagnetic screw 34 while the opposite arm terminates close to the upper end of the core. There is thus given a more intense field for actuation of the diaphragm 12 while the intensity of the field at the opposite end of the electro-magnet is decreased so as to insure rapid vibration of the spring plate 23 which is of very light metal.

What is claimed is:

A device for producing sounds in imitation of wireless telegraphic signals, comprising an electro-magnet, a paramagnetic member in the field force between the poles of the electro-magnet and capable of absorbing a portion only of the magnetic lines of force of the field of the magnet and spaced at one end from a pole of the magnet, a diaphragm in the field of the electro-magnet across the spacing between the last named pole and the paramagnetic member and a make and break mechanism in circuit with the electro-magnet and subject to lines of force exterior to the paramagnetic member.

In testimony whereof I affix my signature in the presence of two witnesses.
